(57) **CLAIM**

The ornamental design for an elastic membrane for semiconductor wafer polishing, as shown and described.

DESCRIPTION

FIG. 1 is a front view of an elastic membrane for semiconductor wafer polishing showing our new design;

FIG. 2 is a rear view thereof;

FIG. 3 is a plain view thereof;

FIG. 4 is a bottom view thereof;

FIG. 5 is a right side view thereof;

FIG. 6 is a left side view thereof;

FIG. 7 is a cross section view taken along the line 7-7 of FIG. 2 thereof;

FIG. 8 is a enlarged view of part 8 of FIG. 7 thereof; and, FIG. 9 is an enlarged view taken of portion 9-9' of FIG. 8 thereof.

The broken lines depict environmental subject matter only and form no part of the claimed design.
